214,041

COMBINED SEATING AND TABLE UNIT

Don S. Shoemaker, % Senal, S.A., Santa Maria de Guido,
Morelia, Michoacan, Mexico

Original design application Dec. 6, 1965, Ser. No. 74,
now Patent No. 208,649, dated Sept. 26, 1967. Divided
and this application Aug. 28, 1967, Ser. No. 9,552

Term of patent 14 years

Int. Cl. D6—01

U.S. Cl. D15—1

FIG. 2

FIGURE 1 is a front perspective view of a combined seating and table unit showing my design; and
FIGURE 2 is a rear perspective view thereof.

This is a division of design application, Ser. No. D.74, filed Dec. 6, 1965, now Patent No. D.208,699.

I claim:

The ornamental design for a combined seating and table unit, as shown.
